(57) CLAIM

The ornamental design for a Minnesota shaped layered sponge and scrub, as shown and described.

DESCRIPTION

FIG. 1 is a front perspective view of my design for a Minnesota shaped layered sponge and scrub including a scrub layer of a porous, open celled construction and a sponge layer;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

FIGS. 1-3 show a heart-shaped hole in broken lines. The broken lines form no part of the claimed design.

1 Claim, 7 Drawing Sheets
